UNITED STATES PATENT OFFICE.

JOHN T. STONEY, OF LAKWOOD, AND KLEMENS PURWIN, OF CLEVELAND, OHIO, AS-
SIGNORS TO THE STONEY FOUNDRY ENGINEERING AND EQUIPMENT CO., OF CLE-
VELAND, OHIO, A CORPORATION OF OHIO.

METHOD OF VIBRATING OBJECTS.

Original application filed September 12, 1921, Serial No. 500,193. Divided and this application filed April 18, 1924. Serial No. 707,396.

To all whom it may concern:

Be it known that we, JOHN T. STONEY, a resident of Lakewood, and KLEMENS PURWIN, a resident of Cleveland, both in county 5 Cuyahoga, and State of Ohio, both citizens of the United States, have jointly invented a new and useful Method of Vibrating Objects, of which the following is a specification.

10 The subject matter of the present application was originally disclosed and presented in our application for method and apparatus for shaking out foundry flasks and the like, filed September 12, 1921, Serial No. 15 500,193, and was divided out of that application on April 11, 1924.

Our invention relates to methods of creating vibrations in objects.

The main object of our invention is a 20 simple, inexpensive, and effective method of vibrating objects for such purposes as loosening adherent matter from objects, or ejecting matter from an object, for instance. Other objects will appear, or become apparent or obvious during the description of 25 the apparatus shown in the accompanying drawing and the operation thereof.

Our invention is illustrated in the accompanying drawing which shows certain mechanism or apparatus engaging a certain foundry flask and adapted to vibrate the same, for the purpose of carrying out our method. It is understood, however, that apparatus other than that shown can be employed to 30 vibrate the flask shown, that the apparatus shown can vibrate objects other than the flask shown, and that apparatus other than that shown can be employed to vibrate objects other than the flask shown, within the 35 scope of the appended claims.

Irrespective of the apparatus employed, or the object to be vibrated, the present invention contemplates that the object is suspended in some manner, preferably so that the 40 major body portion thereof is free to vibrate in all directions. Such expediencies as merely laying the object on a table or other similar support and slowly jarring this table or support, as in a molding machine for instance, is not included in the present invention and is not contemplated therein, but it is contemplated to so dispose the object, in relation to the suspension mechanism, that the

object can respond freely to sharp and rapid vibrations created in the suspension mechanism.

The accompanying drawing contains one perspective view showing a flask suspended on a crane hook which has an air pressure vibrator incorporated in each leg.

Referring now particularly to the drawing,

The flask A is the object to be vibrated for the purpose of loosening whatever sand may have adhered to the inside of the walls there- 45 of due to previous casting operations.

This flask A is provided with the usual trunnions 10 which form a convenient means for suspending the flask in this instance.

The suspension means shown comprises a 50 crane hook having two legs B, each leg mainly of chain formation in the present instance, joined at the top by the ring 11, and provided with the hook 12 at the bottom to engage the respective trunnion.

In the present instance, the legs B are spaced apart by the adjustable spacer bars C so that those portions of the legs which contain the vibrators D are disposed substantially vertical to favor the particular 55 type of vibrators shown.

The vibrators D are connected or incorporated in the legs B and are secured to the chain portions thereof by the bolts 13 passing through the plates 14 and the ears 15 60 of the present vibrator.

Each of the vibrators shown is of the pressure air type well known in the art, each having the previously mentioned ears 15.

Pressure air, or other similar pressure 65 fluid, operating in an apparatus similar to an air hammer, are convenient and effective means for carrying out the present method since they produce rapid and sharp vibrations in an economical manner. It is ob- 70 vious, however, that other vibrator devices may be employed as long as the vibrations created thereby are sufficiently sharp, or rapid, or both, to vibrate the flask for the purpose in hand.

In operation, when the vibrators are in 75 operation vibrations are created in the housing thereof due to the plunger in the vibrator device striking the anvil block in the housing.

These vibrations are transmitted to the

ears 15 and from there into the legs and into the hooks 12. Since the hooks contact the trunnions 10, these vibrations are transmitted from the hooks into the trunnions and into the main body of the flask.

Since the flask is so suspended that the major portion thereof is free to vibrate in all directions, the vibrations set up in the trunnions cause this body to vibrate sufficiently severe to loosen matter adhering on the flask or to remove or eject matter from the flask.

In order to get best results in a method as above described, the main or major portion of the body of the object should be free to vibrate in all directions as previously stated. The trunnions on the flask shown provide a convenient means for suspending the flask to permit such free vibration. It is not necessary, however, that the object should be suspended from a plurality of points on the outside thereof although such means of suspension gives very good results. A single suspension of the object, from the center of gravity for instance, will answer the purpose as long as the major portion of the body is free to vibrate.

We are aware that modifications can be made in the method and means of suspension shown as well as in the method and means for creating vibrations shown, therefore, without limiting ourselves to the precise method and apparatus set forth,

We claim:—

35 1. The method of vibrating objects, comprising, suspending an object to be vibrated, and creating vibrations in the means on which said object is suspended.

2. The method of vibrating objects, comprising, suspending an object to be vibrated so that the main body portion thereof is free to vibrate in all directions, and creating vibrations in the means on which said object is suspended.

40 3. The method of vibrating objects, comprising, suspending an object to be vibrated by a plurality of outer points thereof, and creating vibrations in the means on which said object is suspended.

45 4. The method of vibrating a foundry flask, comprising, suspending said flask by the trunnions thereof, and creating vibrations in the means on which said flask is suspended.

50 5. The method of vibrating objects, comprising, suspending an object to be vibrated, and creating vibrations in the means on which said object is suspended by a pressure fluid vibrator.

55 6. The method of vibrating objects, comprising, suspending an object to be vibrated, and creating sharp and rapid vibrations in the means on which said object is suspended.

60 7. The method of vibrating objects, comprising, suspending an object to be vibrated, and creating vibrations in the means on which said object is suspended by an air pressure vibrator.
